US0D1051882S

(12) **United States Design Patent** (10) **Patent No.:** **US D1,051,882 S**
Nguyen et al. (45) **Date of Patent:** **** Nov. 19, 2024**

(54) **RFID INLAY**

- (71) Applicant: **CCL Label, Inc.**, Framingham, MA (US)
- (72) Inventors: **Henry Nguyen**, Holland, MI (US); **Michael Isabell**, East Grand Rapids, MI (US)
- (73) Assignee: **CCL Label, Inc.**, Framingham, MA (US)
- (**) Term: **15 Years**

(21) Appl. No.: **29/893,633**(22) Filed: **Jun. 1, 2023**

(51) LOC (14) Cl. **14-03**
(52) U.S. Cl. **USPC D14/230**

(58) **Field of Classification Search**

USPC D14/230, 231–240, 299, 343, 489, 492, D14/138, 135; D13/182; D12/42–43
